PULP MOLDING MACHINE

Alfred E. Comstock, Palmer, Mass., assignor, by mesne assignments, to Diamond Gardner Corporation, a corporation of Delaware

Application July 16, 1952, Serial No. 299,213

14 Claims. (Cl. 92—56)

This invention relates to pulp molding machines of the type comprising a rotatable frame provided with a series of molding dies on which the pulp articles are formed and conveyor carried drying forms to which the articles are transferred for movement to drying or finishing mechanism, and is more particularly concerned with improved mechanism for controlling the relative movement of the molding dies and drying forms to permit the transfer of the articles from the former to the latter while continuously rotating the die carrying frame and continuously moving the drying form conveyor.

It is a general object of the invention to provide an improved pulp molding machine wherein a series of forming dies are mounted on a rotatable frame which is so positioned relative to a container having therein a supply of liquid pulp material that the foraminous and contoured outer or molding faces of the dies are immersed in the fluid material, upon rotation of the frame, for a sufficient length of time to accumulate thereon, by means of suction applied to the interior of the molding face, a layer of pulp forming an article of the desired shape and wherein a series of drying forms are arranged on an endless conveyor having one end thereof supported adjacent the forming die frame with a combined means for driving both the rotatable forming die frame and the conveyor and for aligning the contoured outer face of each drying form with a forming die to permit transfer of the still wet and soft molded pulp article from the forming die to the drying form while they are in substantially parallel spaced relation whereby there is no scuffing or damaging of the article while the drying form and forming die are brought into and out of face alignment and while the article is transferred from one to the other.

It is a more specific object of the invention to provide a pulp molding apparatus comprising a rotatable frame having a forming die thereon adapted to receive on a foraminous molding face thereof a layer of wet pulp forming a molded article, a driven conveyor having a drying form thereon with a face which is complementary to the molding face of the forming die, the rotatable frame and the conveyor being so arranged that the complementary faces on the drying form and the molding die may be brought into opposed relation, means on the rotatable frame and the drying form adapted to be interengaged for a predetermined period of time to tilt the drying form and hold the face thereof in substantially aligned, parallel, spaced relation with the face of the forming die and with the die carrying frame being rotated by movement of the conveyor and means to transfer the molded article from the forming die to the drying form while the faces thereof are held in aligned parallel relation.

It is another object of the invention to provide a pulp molding machine having a rotatable frame on which a plurality of forming dies are peripherally spaced, each of the dies having a foraminous contoured outer face which is adapted to receive a layer of wet pulp forming

2

the molded article, and a continuous sprocket driven chain conveyor having a plurality of drying forms arranged on the links thereof, each of the drying forms having an outer face complementary to the contoured face of a forming die, the chain conveyor being arranged with the drive sprocket above and somewhat beyond the rotatable die carrying frame so that the lower reach of the conveyor travels in a horizontal plane generally parallel with and somewhat below a plane tangent to the top point of the path of the forming dies, and movable tooth-like formations on the forming die frame which are operated to engage the pivot connections between the chain links as they approach the die carrying frame whereby to tilt the trailing end of each link and align the face of the drying form thereon with the face of a forming die and to bring the faces of the drying form and forming die into opposed parallel relation whereby to permit movement of the same toward and from each other in parallel relation while the wet and soft molded pulp article is transferred from the forming die to the drying form, with the die carrying frame being rotated by engagement of the tooth-like formations with the driven chain links.

It is another object of the invention to provide a pulp molding machine comprising a rotatable drum on which a plurality of forming dies are peripherally spaced, each of the dies having an outer foraminous face which is contoured to receive a layer of wet pulp forming the molded article, and an endless sprocket driven chain conveyor having a plurality of drying forms arranged in fixed relation on the links thereof, each of the drying forms having an outer face which is complementary to the contoured face of a forming die, the chain conveyor being arranged so that the lower reach of the conveyor travels in a horizontal plane above the forming die drum, and radially movable means on the drum for engagement with the pivot connections between the chain links on the conveyor as they move into the path of movement of the forming dies to tilt each link and align the face of the drying form thereon with the face of an oncoming forming die and position the complementary faces for movement in opposed parallel relation and toward and from each other while the wet and soft molded pulp article is transferred from the forming die to the drying form, with the chain engaging means rotating the forming die frame in synchronism with the movement of the chain conveyor.

These and other objects of the invention will be apparent from a consideration of the apparatus which is shown by way of illustration in the accompanying drawings, wherein:

Fig. 1 is a view partly in side elevation and partly in section of apparatus forming a portion of a molding machine which incorporates therein the principal features of the invention;

Fig. 2 a view partly in elevation and partly in section, the view extending in a direction axially of the molding or forming cylinder and having portions broken away; and

Figs. 3, 4 and 5 are detail views, partially in side elevation and partially in section, and to an enlarged scale, showing the movement of the molding die and drying form adjacent the point where the transfer of the molded article is effected.

Referring to the drawings, there is illustrated apparatus forming a portion of a molding machine which incorporates therein various features of the invention and which is particularly adapted for the manufacture of a molded pulp article, such as an egg carton, or a similar article, requiring a forming die having a molding face which is characterized by projecting portions of substantial size separated by relatively deep valleys or recesses. Only

that portion of the molding machine is illustrated which has to do with the depositing of the pulp on the molding face of the forming die to form the article and the transfer of the same to a drying form on a traveling conveyor which transports the article to the drying and finishing apparatus. Since the apparatus for drying and finishing the article forms no part of the present invention it is not illustrated.

The illustrated apparatus comprises a turret or molding cylinder 10 which is rotatably supported on a horizontal shaft or axle 11 and which carries thereon in spaced relation around the periphery thereof a plurality of forming dies 12. The cylinder 10 is arranged for rotating movement about the axis of the shaft 11 directly above the open top of a container or vat 13 which is supplied with a quantity of liquid pulp material 14. The pulp material or slurry 14 comprises pulp fibers in water or other liquid of a consistency which will permit deposit of the pulp fibers in a continuous layer on the outer surface of a foraminous or perforated face of the forming die 12 by suction applied to the interior surface of the molding face. The cylinder 10 is arranged on its shaft above the open container 13 so that, upon rotation of the cylinder 10, the dies 12 have their molding faces immersed in the liquid material 14 as they traverse the lower portion of their path to permit accumulation thereon of a uniform layer of the wet pulp fibers. The liquid material 14 is maintained at a predetermined level 15 in the container 13 by a supply line (not shown) and the layer of the wet pulp fibers is accumulated on each successive die 12 as the molding face of each die passes through the material 14, the direction of rotation of cylinder 10 being clockwise as indicated by the arrows in Fig. 1.

An endless chain conveyor 16 is supported at one end on a sprocket formation 17 arranged on a shaft 18 which is parallel with the shaft 11 and spaced above the same slightly forwardly thereof in the direction of rotation of the cylinder 10, so that the lower run of the conveyor 16 passes between the cylinder 10 and the sprocket formation 17 as it commences to move in a circular path around the sprocket 17. A plurality of drying frames 19 are mounted on the conveyor 16 and extend between oppositely disposed links 20 of the chains which form the side members of the conveyor 16. The drying frames 19 are adapted to receive the still wet and soft layer of pulp forming the molded article from the forming dies 12 on the cylinder 10 and to carry the same around the sprocket formation 17 and over the top run of the conveyor 16 to the drying and finishing apparatus, the molded articles being removed from the machine when the drying and finishing operations are completed.

The shaft 11 supporting the cylinder 10 is mounted in suitable end bearings 21 in laterally spaced side plates 22 forming portions of the supporting frame for the machine. The body of the cylinder 10 comprises a plurality of wheel-like sections 23 in aligned relation axially of the shaft 11. Each of the sections 23 comprises a hollow hub-like portion 24 keyed to the shaft 11 and having spoke-like formations 25 extending in a generally radial direction and which are aligned with like formations in the adjoining sections. The spoke formations 25 are hollow and provide radially extending passageways 26 which are in communicating relation with axially extending passageways 27 in the hub-like portions 24. The spoke formations 25 are separated by web portions 28. Each spoke formation 25 extends to a flat surface 29 forming a portion of the periphery of the cylinder 10. Each of the flat surfaces 29 carries an axially extending supporting member 30 for the forming dies 12, a plurality of the dies 12 being arranged in axially spaced relation across the cylinder 10.

Each of the forming dies 12 comprises the open face box-like support 30 and a foraminous screen 32 which forms the outer or molding face of the die. The screen 32 is contoured to provide the desired shape for the molded

article. When the article is a carton of the type employed in the packaging of eggs, the outer face of the screen 32 includes projecting portions 33 (Figs. 3 to 5) and recesses 34 which are of substantial depth.

At the ends of the cylinder 10 the end face of each end section 23 is provided with an end plate 35 having apertures 36 conforming to the passageways 27 in the hub section of the cylinder. A channel-like edge formation 37 on the periphery of the end plate 35 receives in rotatable relation a flange formation 38 on the periphery of the inner face of the two-part suction box 39 which is secured in fixed relation at the end of the shaft 11. The suction box 39 is provided with an inner bearing portion or sleeve 40 permitting the shaft 11 to extend through the same. The suction box 39 is divided into compartments 41, 42 and 43 which are connected by suitable lines 44, 45 and 46 (Fig. 2) to suction and blow off apparatus (not shown). The inner face of the suction box 39 is apertured to provide communication between the passageways 27 in the cylinder 10 and the suction and blow off compartments 41, 42 and 43 during rotative movement of the dies 12 through the container 13 and up to the point where the pulp article is transferred to the drying form 19.

Between each of the dies 12 on the periphery of the cylinder 10 a movable tooth formation 47 is provided which is arranged at one end of an elongated plate 48. The other end of each plate 48 is pivoted at 49 adjacent the peripheral margin of an end plate 50 which is secured to the end section 23 on the cylinder 10 and rotates with the same. Each tooth formation or member 47 is provided with a cam roller 51 which is adapted to engage a fixed cam 52 mounted on a bracket 53 extending from the side frame plate 22. The tooth forming members 47 are provided with outwardly opening semi-circular sockets 54 which are moved by the cam 52 into engagement with successive pivot pins 55 connecting the links 20 of the chain conveyor 16. The plates 48 are mounted for swinging movement about pivots 49 with conventional means, such as a pin and slot 56, for limiting the extent of the movement.

The sprocket formation 17 which supports the end of the conveyor 16 comprises a central hub portion 60 which is hollow, providing axially extending passageways 61. The passageways 61 are connected at the ends of the sprocket with a suction compartment (not shown) in a fixed suction box 62, the compartments being connected by a line 63 with a suction device.

The drying frames 19 are secured between the chain links 20 by brackets 64 and comprise a box-like body portion 65 and a plurality of perforated or foraminous screens or forms 66 which extend axially of the frames 19 and in spaced relation corresponding to the forming dies 12. The screens or forms 66 are shaped to mate with the screens 32 of the dies 12. They include projecting portions 67 and separating recesses 68 which are complementary to the recesses 34 and projections 33 of the screens 32.

A plurality of suction boxes 69 are provided which are mounted in spaced relation about the periphery of the sprocket formation 17. Each box 69 is mounted on a pivot 70 extending along the leading edge of the box and in axial alignment with a tooth on the sprocket formation. A cam roller 71 is provided at each end of the box on an axis extending adjacent the trailing edge of the box, opposite the pivot 70. The cam roller 71 is received in a cam track 72 secured by brackets 73 in fixed relation to the side frame plate 22 which controls the tilting or pivotal movement of the suction box 69 as it travels around the curved path of the sprocket 17. Each of the suction boxes 69 is connected by a suitable hose line 74 to a suction compartment or passageway 61 in the hub portion of the sprocket formation 17. The outer or open face of each of the suction boxes 69 is provided with a gasket 75 for sealing engagement with

the inner open face of a drying frame 65. The arrangement of the drying frames 65 and the suction boxes 69 is such that upon movement of the drying frames 65 into the circular path of the sprocket 17 a suction box 69 is aligned with the drying frame so that the hollow interiors of the two box-like members are in communicating relation and form, with the hose connection 74 and passageway 61, a continuous passageway for the application of suction through the perforated forms 66.

The movable teeth 47 on the molding cylinder 10 are adapted to engage with successive pivot pins 55 connecting the links 20 of the chain conveyor 16 as the lower run of the conveyor 16 reaches a point just prior to engagement with the end sprocket formation 17. The cam 52 is arranged to elevate the teeth 47 in such a manner that each drying frame 19 is tilted (Figs. 3 to 5) as it approaches a die 12 on the cylinder 10 and brought into parallel relation with the die 12 as they move into relatively close parallel relation. Just prior to the point where the die 12 passes through the vertical center of the molding cylinder 10 the cam 52 causes the leading end of the oncoming frame 19 to be raised out of its normal horizontal path so that the opposed form 66 and molding screen 32 approach each other at a less acute angle in order to avoid interference between the projecting portions 33 and 67. As the die 12 reaches its uppermost point the faces of the die 12 and its mating frame 19 move toward each other while traveling in very nearly parallel relation for a predetermined portion of their linear movement, sufficient to permit transfer of the wet pulp article from the die 12 to the drying frame 19 while they are aligned and passing between the cylinder 10 and the lower run of the conveyor 16. The engagement of the teeth 47 with the pivots 55 connecting the chain links 20 serves to drive the cylinder 10 in synchronism with the conveyor 16 which is in turn driven by a gear 76 connected to a suitable source of power (not shown).

I claim:

1. In a molding apparatus, a rotatable frame, a forming die carried on said frame and having a molding face on the periphery thereof adapted to receive thereon a layer of pulp material forming a molded article, a link chain conveyor having upper and lower runs, a driven sprocket arranged immediately adjacent and above said frame, said sprocket supporting one end of said conveyor, a drying form carried on a chain link and having a face complementary to the molded face of said layer of pulp, said sprocket and said frame being arranged on vertically spaced axes so that the lower run of the conveyor chain advances toward said sprocket in a plane generally parallel to a plane which is tangent to and somewhat below the top point in the path of said forming die and then moves upwardly around said sprocket away from the path of movement of said forming die whereby the faces of said forming die and said drying form may be brought into parallel spaced relation as they approach each other and advance simultaneously over a predetermined portion of their paths, and interengaging means on said frame and said conveyor to tilt the chain link on which the drying form is carried about a transverse axis and out of its normal path of advancing movement as the drying form and forming die approach each other and decrease the angle of approach of the faces thereof, said interengaging means causing the faces of the forming die and drying form to move toward and from each other in parallel alignment during a predetermined linear movement and thereafter to move away from each other in angular relation.

2. In a molding apparatus, a rotatable drum, a forming die fixed on said drum and having a molding face on the periphery thereof adapted to receive thereon a layer of pulp material forming a molded article, a link chain conveyor having upper and lower runs, a driven sprocket supporting one end of said conveyor, a drying form car-

ried on a chain link and having a face generally complementary to the molding face on the forming die, said sprocket and said drum being arranged immediately adjacent each other so that the lower run of the conveyor chain normally moves in a straight path toward the upper periphery of the path of a forming die on said drum as said lower run advances in the same direction as the direction of advancing movement of said drum and then passes upwardly around its supporting sprocket away from said drum whereby the faces of said forming die and said drying form are brought into predetermined parallel spaced relation above said drum, and interengaging means on said drum and said conveyor arranged to tilt the chain link on which the drying form is carried out of its normal path and decrease the angle of approach of the opposed faces of the drying form and forming die as they approach each other, said interengaging means aligning said drying form with said forming die and causing the faces thereof to move toward and from each other in parallel alignment during a portion of the movement of the forming die and drying form immediately preceding their closest approach to each other.

3. In apparatus for molding pulp articles, a container having a liquid pulp material therein, a molding member, means supporting said molding member for continuous rotative movement above said container, said molding member being mounted on said supporting means so that upon rotation of the same the outer face is moved through the liquid pulp material, the outer face of said molding member being adapted to receive thereon a layer of the wet pulp as it moves through the liquid pulp material, an endless conveyor, means adjacent said molding member supporting means for supporting one end of said conveyor for continuous movement along a lower run and upwardly around the supporting means therefor and away from said molding member supporting means, a drying form member on said endless conveyor, said drying form member having a face which is complementary to the outer face of said layer of wet pulp, said supporting means being spaced relative to each other and being operated to advance the molding member and the drying form member toward each other and into close proximity along a portion of the path of movement of said members, and mechanism operative on said drying form conveyor to move said conveyor out of its normal path and tilt said drying form relative to said path so as to reduce the angle of approach of the face of said drying form and the face of said molding member as said drying form member approaches said molding member to bring the face of said drying form into opposed, spaced, parallel and aligned relation with the face of the continuously advancing molding member for a predetermined period of movement of said conveyor during which said molding form and said drying form pass between said conveyor end supporting means and said molding member supporting means to permit transfer of the layer of pulp from the molding member to the drying form during said period and without interrupting the advancing movement of said conveyor and said molding member supporting means.

4. In a pulp molding machine, a container having a supply of liquid pulp material therein, a continuously rotating drum mounted above said container, a forming die having a molding face mounted in fixed relation on said drum, a continuously moving endless conveyor having one end supported adjacent said drum, a drying form mounted on said conveyor and having a face generally complementary to said molding face, means for rotating said drum and for moving said conveyor with a continuous and substantially uniform movement to bring said forming die and said drying form into opposed relation while said drum and said conveyor are continuously advancing said forming die and said drying form, and means operative on said conveyor to bodily swing said drying form relative to the normal path of movement of the conveyor there-

by to reduce the angle of approach of the face of the drying form and the face of the forming die and bring the face of the drying form into a plane generally parallel to and spaced from the molding face on said forming die as said forming die and said drying form advance toward each other and move between said drum and the end of said conveyor, without interrupting the advancing movement of said drying form and said forming die.

5. In a pulp molding machine, a container having a supply of liquid pulp material therein, a rotating cylinder mounted above said container, a forming die having a molding face mounted on said cylinder, a chain link conveyor, a rotating sprocket mounted immediately above said cylinder and supporting one end of said conveyor, a drying frame rigidly secured to a chain link on said conveyor, said drying frame having a drying form thereon with a face generally complementary to said molding face, means for rotating said cylinder and said sprocket in opposite directions with a continuous uniform movement and in timed relation whereby said drying frame is advanced toward said cylinder along the lower run of said conveyor in a path which is normally straight and then passes upwardly around said sprocket and said forming die and said drying frame are brought into oppositely disposed aligned relation during a portion of their movement, and means for engaging said conveyor link to move said link upwardly out of the normal path of movement thereof and to reduce the angle of approach of said drying form and molding faces and bring the face of said drying frame into generally parallel spaced relation with the molding face on said forming die as said drying frame and forming die approach each other and move in aligned relation between said cylinder and said sprocket.

6. In a molding apparatus, a rotatable drum, a forming die fixed on said drum and having a molding face adapted to receive thereon a layer of pulp material forming a molded article, a chain link conveyor having upper and lower runs, a driven sprocket supporting one end of said conveyor immediately adjacent said drum, a drying form carried on a chain link and having a face complementary to said molding face, said sprocket and said conveyor being positioned vertically so that the lower run of the conveyor chain advances in a normally straight line path above said drum and then moves upwardly about said sprocket whereby the complementary faces of said forming die and said drying form are advanced toward each other into parallel spaced relation, and interengaging means on said drum and said conveyor which is operative upon engagement to tilt the leading end of the chain link on which the drying form is carried relative to the normal path of movement of said lower run and decrease the angle of approach of the faces of the drying form and forming die as they advanced toward each other, said means being operative to cause the faces thereof to move toward each other into parallel alignment during a predetermined portion of the movement of the forming die and drying form immediately preceding their closest approach to each other.

7. In a molding apparatus, a rotatable cylinder, a forming die carried on said cylinder and having a molding face adapted to receive thereon a layer of pulp material forming a molded article, an endless conveyor having upper and lower runs, a driven sprocket supporting one end of said conveyor adjacent the top of said cylinder, said conveyor comprising laterally spaced link chains, a drying frame supported between opposed links of said chains and having a face generally complementary to the molding face of said forming die, said sprocket and said conveyor being arranged so that the lower run of the conveyor advances in a plane normally parallel to a horizontal plane which is tangent to the top point in the path of said forming die and then moves upwardly around its supporting sprocket and away from the path of movement of said forming die whereby the faces of said forming die and said drying frame may be brought

into parallel relation, and means on said cylinder engageable with the chain links on said conveyor to tilt the chain links on which the drying frame is carried upwardly from their normal path immediately adjacent a point where the

5 drying frame and forming die approach their closest relationship with each other, whereby the angles of approach and separation of the faces thereof are decreased as they move toward and from each other and pass between said cylinder and said sprocket.

10 8. A molding machine comprising a rotatably mounted cylinder, a plurality of forming dies mounted in fixed spaced relation around the periphery of the cylinder, a container having a supply of liquid pulp material therein, said dies moving through the pulp material at the bottom

15 of their rotational path, means associated with the dies to deposit thereon a layer of the pulp as they pass through the liquid material, an endless link chain conveyor, a plurality of drying forms supported on the links of the conveyor, a sprocket rotatably mounted above said cylinder and supporting one end of said conveyor, means for driving said sprocket, means on said cylinder engaging

20 said conveyor for driving said cylinder in timed relation to said conveyor whereby to align the drying forms on the conveyor with successive dies on the cylinder, suction

25 boxes pivotally mounted on the sprocket, cam rollers mounted on each suction box and a fixed cam track controlling the pivotal movement of the suction boxes whereby to engage each drying form to connect the same with a suction line as the drying forms move around the sprocket, and means to bring the faces of the drying forms into parallel relation to the faces of the forming dies when they are in alignment between the cylinder and the sprocket.

30 9. A molding machine comprising a rotatably mounted cylinder, a plurality of forming dies mounted in spaced relation around the periphery of the cylinder, a container having a supply of liquid pulp material therein, said dies moving through the pulp material at the bottom of their rotational path, means associated with the dies to deposit

35 thereon a layer of the pulp as they pass through the liquid material, an endless conveyor having laterally spaced chain links, a plurality of drying forms supported between the chain links, a sprocket rotatably mounted above said cylinder and supporting one end of said conveyor, means for driving said sprocket, chain actuated means for driving said cylinder in timed relation to the movement of the conveyor to align the drying forms on the conveyor with successive dies on the cylinder, suction

40 boxes pivotally mounted on the sprocket, means to control the pivotal movement of said suction boxes to engage each drying form and connect the same with a suction line as the drying forms move around the sprocket, and means to control the movement of the conveyor chains whereby to bring the faces of the drying forms into parallel relation to the faces of the forming dies while they are in alignment between the cylinder and the sprocket.

45 10. A molding machine comprising a rotatably mounted cylinder, a series of forming dies mounted in spaced relation around the periphery of the cylinder, a container beneath said cylinder, said container having a supply of liquid pulp material therein, the cylinder and the container being arranged so that the dies move through the liquid material at the bottom of their rotational path,

50 means to deposit on the dies a layer of the pulp as they pass through the liquid material, an endless link chain conveyor, a series of drying forms supported on the chain links of the conveyor, a sprocket formation rotatably mounted above said cylinder and supporting one end of

55 said conveyor, means for driving said sprocket formation, means on said cylinder engaging said conveyor for driving said cylinder in timed relation to the movement of said conveyor whereby to align the drying forms on the conveyor with the dies on the cylinder, suction boxes

swingably mounted on the sprocket formation, means controlling the swinging movement of the suction boxes whereby to engage the same with the drying forms to connect each form with a suction line as the drying forms move around the sprocket formation, and means to bring the faces of the drying forms and forming dies into parallel relation when they are in alignment between the cylinder and the sprocket formation.

11. A molding machine comprising a rotatably mounted cylinder, a series of forming dies arranged in spaced relation around the periphery of the cylinder, a container beneath said cylinder having a supply of liquid pulp material therein, the cylinder and container being arranged so that the dies move through the liquid material at the bottom of their rotational path, means to deposit on the dies a layer of the pulp as they pass through the liquid material, and endless conveyor having laterally spaced chain links, a series of drying forms supported between the links of the conveyor, a sprocket formation rotatably mounted above said cylinder and supporting one end of said conveyor, means for driving said sprocket formation, means on said cylinder engaging said conveyor for driving said cylinder in timed relation to said conveyor whereby to align the drying forms on the conveyor with the dies on the cylinder, suction box formations mounted on the sprocket formation for movement relative to said sprocket formation, means associated with said sprocket formation for controlling the movement of the suction box formations relative to said sprocket formation whereby to engage the same in operative relation with the drying forms as the drying forms move around the sprocket formation, and means on said cylinder engaging said conveyor to bring the faces of the drying forms into parallel relation to the faces of the forming dies as they move into alignment between the cylinder and the sprocket formation.

12. A molding machine comprising a rotatably mounted cylinder, a series of forming dies mounted in spaced relation around the periphery of the cylinder, a container beneath said cylinder having therein a supply of liquid pulp material at a height sufficient for the dies to move through the same at the bottom of their rotational path, means to deposit on the dies a layer of the pulp as they pass through the liquid pulp material, an endless conveyor having laterally spaced chain links, a series of drying forms supported on said chain links, an end sprocket rotatably mounted above said cylinder and supporting one end of said conveyor, means for driving said sprocket, means on said cylinder engaging with said conveyor for driving said cylinder when said conveyor is driven by said sprocket in timed relation to said conveyor whereby to align the drying forms on the conveyor with the dies on the cylinder, said last mentioned means being arranged to bring the faces of the drying forms into parallel relation with the faces of the forming dies as they move into alignment between the cylinder and the sprocket, suction boxes mounted on the sprocket for movement relative to said sprocket, and cam means associated with said sprocket and said suction boxes for moving the suction boxes relative to said sprocket whereby to engage the same in operative relation with the drying forms as the drying forms move around the sprocket.

13. A molding machine comprising a rotatably mounted cylinder, a series of forming dies mounted in spaced relation around the periphery of the cylinder, a

container beneath said cylinder having therein a supply of liquid pulp material at sufficient height for the dies to move through the same at the bottom of their rotational path, means to deposit on the dies a layer of the pulp as they pass through the liquid material, an endless conveyor having laterally spaced chain links, a series of drying forms supported on said chain links, a sprocket rotatably mounted above said cylinder and supporting one end of said conveyor, means for driving said sprocket, suction boxes mounted on the sprocket for movement relative to said sprocket, cam means for moving the suction boxes relative to said sprocket upon rotation of said sprocket whereby to engage the same in operative relation with the drying forms as the drying forms move around the sprocket, tooth formations movably mounted on said cylinder, and means for moving said tooth formations relative to said cylinder and into engaging relation with said conveyor for driving said cylinder in timed relation to said conveyor when said conveyor is driven by said sprocket whereby to align the drying forms on the conveyor with the dies on the cylinder, said tooth formations being moved into engagement with the drying forms on the conveyor to tilt the drying forms and bring the faces of the drying forms and forming dies into parallel relation as they move into alignment between the cylinder and the sprocket.

14. A molding machine comprising a rotatably mounted cylinder, a series of forming dies mounted in spaced relation around the periphery of the cylinder, a container beneath said cylinder having therein a supply of liquid pulp material at a sufficient height for the dies to move through the same at the bottom of their rotational path, means to deposit on the dies a layer of the pulp as they pass through the liquid material, an endless conveyor having laterally spaced chain links, a series of drying forms supported on the chain links of the conveyor, a sprocket rotatably mounted above said cylinder and supporting one end of said conveyor, means for driving said sprocket, radially movable teeth on said cylinder engaging said conveyor for driving said cylinder in timed relation to said conveyor whereby to align the drying forms on the conveyor with the dies on the cylinder, suction boxes swingably mounted on the sprocket, a fixed cam means controlling the swinging movement of the suction boxes whereby to engage the same with the drying forms as the drying forms move around the sprocket, and means to move said teeth radially of the cylinder to bring the faces of the drying forms into parallel relation to the faces of the forming dies as they move into alignment between the cylinder and the sprocket.
